(57) **ABSTRACT**

The area necessary to install the liquid jet head to be positioned by a positioning mechanism is reduced. An inkjet head is provided with a head main body for jetting ink, a base member which supports the head main body, and is installed on an installation surface of a carriage, and a positioning mechanism which adjusts a position of the base member in a direction along the installation surface with respect to a positioning pin disposed on the installation surface, wherein the positioning mechanism is supported by the base member, and at least a part of the positioning mechanism is arranged inside an outer shape of the base member in a plan view of the installation surface viewed from a vertical direction thereof.

LIQUID JET HEAD AND LIQUID JET RECORDING DEVICE

RELATED APPLICATIONS

This application claims priority to Japanese Patent Application No. 2021-173906, filed on Oct. 25, 2021, the entire content of which is incorporated herein by reference.

BACKGROUND OF THE INVENTION

1. Field of the Invention

The present disclosure relates to a liquid jet head and a liquid jet recording device.

2. Description of the Related Art

In JP-A-2005-212347, there is disclosed a recording head positioning structure of adjusting a position of a recording head to a recording head loading part of a printer main body.

This recording head positioning structure is provided with a tilted surface which is provided to the recording head loading part in a state of being tilted with respect to a loading surface of the recording head loading part, and which is tilted with respect to a surface provided to the recording head, and an adjusting member having contact with the surface of the recording head and the tilted surface.

In the positioning structure described above, since a positioning mechanism is disposed laterally to a liquid jet head, the area (a substantial footprint) necessary for an installation of the liquid jet head grows in size, and it is difficult to densely install the liquid jet head to an installation target. Therefore, it is necessary to ensure a large installation surface for the liquid jet head, and thus, there arises a problem of growth in size in particular in a printing width direction of the installation target.

The present disclosure is made in view of the problem described above, and has an object of reducing the area necessary for the installation of the liquid jet head to be positioned by the positioning mechanism.

SUMMARY OF THE INVENTION

(1) A liquid jet head according to an aspect of the present disclosure includes a jet section configured to jet liquid, a base member which is configured to support the jet section, and which is installed on an installation surface of an installation target, and a positioning mechanism configured to adjust a position of the base member in a direction along the installation surface with respect to a protruding part disposed on the installation surface, wherein the positioning mechanism is supported by the base member, and at least a part of the positioning mechanism is arranged inside an outer shape of the base member in a plan view of the installation surface viewed from a vertical direction of the installation surface.

According to this configuration, since the positioning mechanism for positioning the liquid jet head with respect to the protruding part disposed on the installation surface of the installation target is supported by the base member together with the jet section, and at the same time, at least a part of the positioning mechanism is arranged inside the outer shape of the base member in the plan view of the installation surface viewed from the vertical direction, it is possible to arrange the positioning mechanism so as to overlap a footprint of the liquid jet head, and thus, it is possible to

reduce the area necessary to install the liquid jet head. Thus, it is possible to suppress a length in a printing width direction of the liquid jet head to shorten a length in the printing width direction of the installation target necessary when installing a plurality of liquid jet heads.

(2) In the liquid jet head according to the aspect (1), the base member may have a penetration part inside the outer shape of the base member, the protruding part being arranged in the penetration part.

10 In this case, by providing the penetration part to the base member, it is possible to arrange the protruding part inside the footprint of the liquid jet head, and thus, it is possible to further reduce the area necessary to install the liquid jet head.

15 (3) In the liquid jet head according to one of the aspects (1) and (2), the positioning mechanism may include a preloading mechanism configured to apply a preload to the protruding part in a direction along the installation surface, a contact member having contact with the protruding part from an opposite side to a side at which the preloading mechanism is arranged in a direction in which the preloading mechanism applies the preload, and a displacement mechanism configured to displace the contact member in the direction in which the preloading mechanism applies the preload.

20 In this case, by preloading the protruding part with the preloading mechanism to displace the contact member having contact with the protruding part in the preloading direction, it is possible to move the base member following the displacement of the contact member. Since it becomes unnecessary to dispose the contact members and the displacement mechanisms at both sides across the protruding part due to this preloading mechanism, it is possible to achieve simplification, reduction in weight, and reduction in space of the structure of the positioning mechanism.

25 (4) In the liquid jet head according to any one of the aspects (1) through (3), the positioning mechanism may be detachably attached to the base member.

30 In this case, since it is possible to detach the positioning mechanism from the base member after the positioning and the installation of the liquid jet head are completed, and then use the positioning mechanism thus detached for positioning another liquid jet head, the configuration can make a contribution to the reduction in cost.

35 (5) In the liquid jet head according to any one of the aspects (1) through (4), the positioning mechanism may include a first positioning mechanism configured to adjust a position of the base member in a first direction along the installation surface of the base member, and a pair of second positioning mechanisms which are arranged at a distance in the first direction to the base member, and which respectively adjust positions of the base member in a second direction perpendicular to the first direction along the installation surface of the base member.

40 In this case, it is possible to adjust the positions of the base member in the first direction and the second direction along the installation surface due to the first positioning mechanism and the second positioning mechanism. Further, by making the adjustment amount of the position in the second direction different between the pair of second positioning mechanisms, it is possible to adjust the rotational angle of the base member.

45 (6) In the liquid jet head according to the aspect (5), the protruding part may include a first protruding part and a second protruding part arranged across the jet section in the first direction, one of the pair of second positioning mechanisms may adjust a position of the base member in the

second direction with respect to one of the first protruding part and the second protruding part, and another of the pair of second positioning mechanisms may adjust a position of the base member in the second direction with respect to another of the first protruding part and the second protruding part.

In this case, since it is possible to position the liquid jet head with the two protruding parts without disposing three protruding parts so as to correspond respectively to the three positioning mechanisms, namely the first positioning mechanism and the pair of second positioning mechanisms, it is possible to decrease the number of the protruding parts to be arranged in the footprint of the liquid jet head to thereby further reduce the area necessary to install the liquid jet head.

(7) In the liquid jet head according to the aspect (6), the first positioning mechanism may include a preloading mechanism configured to preload one of the first protruding part and the second protruding part in the first direction, a contact member making contact with another of the first protruding part and the second protruding part from an opposite side to a side at which the preloading mechanism is arranged in the first direction, and a displacement mechanism configured to displace the contact member in the first direction.

In this case, by arranging the preloading mechanism at the opposite side to the contact member and the displacement mechanism across the jet section, it is possible to suppress the length in the printing width direction of the base member compared to when arranging all of the preloading mechanism, the contact member, and the displacement mechanism at one side of the jet section. Thus, it is possible to ensure the degree of freedom of the installation space of the liquid jet head.

(8) In the liquid jet head according to one of the aspects (3) and (7), a pressing part protruding toward a side at which the preloading mechanism receives a reactive force from the protruding part in the direction in which the preloading mechanism applies the preload may be provided to the outer shape of the base member.

In this case, when the accuracy of the pressing part is high, it is possible to easily position the liquid jet head by pressing the pressing part against the installation target with the reactive force received by the preloading mechanism from the protruding part. Further, when the accuracy of the pressing part is insufficient, by displacing the contact member toward the opposite side to the pressing direction of the pressing part to adjust the position of the liquid jet head, it is possible to position the liquid jet head.

(9) A liquid jet recording device according to an aspect of the present disclosure includes the liquid jet head according to any one of the aspects (1) through (8), and a carriage as the installation target on which the liquid jet head is installed.

According to the liquid jet recording device related to the present aspect, there can be obtained the liquid jet recording device which is capable of reducing the area necessary to install the liquid jet head, which is compact in size, and which is capable of performing accurate printing.

(10) In the liquid jet recording device according to the aspect (9), the protruding part may be detachably attached to the carriage.

In this case, since it is possible to detach the protruding part from the carriage after the positioning and the installation of the liquid jet head are completed, and then use the protruding part thus detached for positioning another liquid jet head, it becomes possible to reuse the protruding part,

and the configuration can make a contribution to the reduction in cost. Further, it is possible to fix the base member to the carriage using the places where the protruding part is detached.

(11) A liquid jet recording device according to an aspect of the present disclosure includes a liquid jet head, and a carriage on which the liquid jet head is installed, wherein the liquid jet head includes a jet section configured to jet liquid, a base member which is configured to support the jet section, and which is installed on an installation surface of the carriage, and a protruding part protruding from the base member toward the carriage, the carriage is provided with a positioning mechanism configured to adjust a position of the base member in a direction along the installation surface with respect to the protruding part, and at least a part of the positioning mechanism is arranged inside an outer shape of the base member in a plan view of the installation surface viewed from a vertical direction of the installation surface.

According to the liquid jet recording device related to the present aspect, since the liquid jet head is provided with the protruding part, the carriage is provided with the positioning mechanism, and at least a part of the positioning mechanism is arranged inside the outer shape of the base member of the liquid jet head in the plan view of the installation surface viewed from the vertical direction, it is possible to arrange the positioning mechanism so as to overlap the footprint of the liquid jet head, and thus, it is possible to decrease the area necessary to install the liquid jet head. Thus, it is possible to suppress a length in a printing width direction of the liquid jet head to shorten a length in the printing width direction of the installation target necessary when installing a plurality of liquid jet heads.

According to an aspect of the present disclosure described above, it is possible to reduce the area necessary to install the liquid jet head to be positioned by the positioning mechanism.

BRIEF DESCRIPTION OF THE DRAWINGS

FIG. 1 is a schematic configuration diagram of a printer according to an embodiment.

FIG. 2 is a schematic configuration diagram of an inkjet head and an ink circulation mechanism according to the embodiment.

FIG. 3 is a plan view showing an arrangement of the inkjet heads installed in a carriage according to the embodiment.

FIG. 4 is a perspective view of a positioning structure of the inkjet head according to the embodiment.

FIG. 5 is an exploded perspective view of the positioning structure of the inkjet head according to the embodiment.

FIG. 6 is a plan view of the positioning structure of the inkjet head according to the embodiment.

FIG. 7 is a perspective view of a first positioning unit according to the embodiment.

FIG. 8 is a perspective view of a second positioning unit according to the embodiment.

FIG. 9 is a cross-sectional view along an arrow IX-IX shown in FIG. 6.

FIG. 10 is a conceptual diagram for explaining curved surface shapes of contact parts according to the embodiment.

FIG. 11 is an explanatory diagram showing a step subsequent to the positioning of the inkjet head according to the embodiment.

FIG. 12 is a cross-sectional view showing a modified example of the positioning structure according to the embodiment.

DETAILED DESCRIPTION OF THE
PREFERRED EMBODIMENTS

An embodiment according to the present disclosure will hereinafter be described with reference to the drawings.

In the embodiments and modified examples described hereinafter, constituents corresponding to each other are denoted by the same reference symbols to omit the description thereof in some cases. Further, in the following description, expressions representing relative or absolute arrangement such as "parallel," "perpendicular," "center," and "coaxial" not only represent strictly such arrangements, but also represent the state of being relatively displaced with a tolerance, or an angle or a distance to the extent that the same function can be obtained.

In the following embodiment, the description will be presented citing an inkjet printer (hereinafter simply referred to as a printer) for performing recording on a recording target medium using ink (liquid) as an example. It should be noted that the scale size of each member is arbitrarily modified so as to provide a recognizable size to the member in the drawings used in the following description.

[Printer 1]

FIG. 1 is a schematic configuration diagram of a printer 1 according to the embodiment.

As shown in FIG. 1, the printer 1 (a liquid jet recording device) according to the present embodiment is provided with a pair of conveying mechanisms 2, 3, ink tanks 4, inkjet heads 5 (liquid jet heads), ink circulation mechanisms 6, and a scanning mechanism 7.

In the following explanation, the description is presented using an orthogonal coordinate system of X, Y, and Z as needed. An X direction is a conveying direction (a sub-scanning direction) of a recording target medium P (e.g., paper). A Y direction is a scanning direction (a main-scanning direction) of the scanning mechanism 7. A Z direction is a height direction (a gravitational direction) perpendicular to the X direction and the Y direction. It should be noted that the X direction is a printing width direction of the inkjet head 5.

Further, in the following explanation, the description will be presented defining an arrow side as a positive (+) side, and an opposite side to the arrow as a negative (-) side in the drawings in each of the X direction, the Y direction, and the Z direction. In the present embodiment, the +Z side corresponds to an upper side in the gravitational direction, and the -Z side corresponds to a lower side in the gravitational direction.

The conveying mechanisms 2, 3 convey the recording target medium P toward the +X side. The conveying mechanisms 2, 3 each include a pair of rollers 11, 12 extending in, for example, the Y direction. There is disposed a plurality of ink tanks 4 which respectively house ink of four colors such as yellow, magenta, cyan, and black.

There is disposed a plurality of inkjet heads 5 which are configured so as to be able to respectively eject the four colors of ink, namely the yellow ink, the magenta ink, the cyan ink, and the black ink in accordance with the ink tanks 4 coupled thereto.

FIG. 2 is a schematic configuration diagram of the inkjet head 5 and the ink circulation mechanism 6 according to the embodiment.

As shown in FIG. 1 and FIG. 2, the ink circulation mechanism 6 circulates the ink between the ink tank 4 and the inkjet head 5. Specifically, the ink circulation mechanism 6 is provided with a circulation flow channel 23 having an ink supply tube 21 and an ink discharge tube 22, a pressure

pump 24 coupled to the ink supply tube 21, and a suction pump 25 coupled to the ink discharge tube 22.

The pressure pump 24 pressurizes the inside of the ink supply tube 21 to deliver the ink to the inkjet head 5 through the ink supply tube 21. Thus, the ink supply tube 21 is provided with positive pressure with respect to the inkjet head 5.

The suction pump 25 is depressurizes the inside of the ink discharge tube 22 to suction the ink from the inkjet head 5 through the ink discharge tube 22. Thus, the ink discharge tube 22 is provided with negative pressure with respect to the inkjet head 5. The ink circulates between the inkjet head 5 and the ink tank 4 through the circulation flow channel 23 by driving the pressure pump 24 and the suction pump 25.

As shown in FIG. 1, the scanning mechanism 7 reciprocates the inkjet heads 5 in the Y direction. The scanning mechanism 7 is provided with a guide rail 28 extending in the Y direction, a carriage 29 (an installation target) movably supported by the guide rail 28, and a drive device for moving the carriage 29. The drive device is constituted by, for example, a motor, a pulley, and a belt.

<Inkjet Heads 5>

The inkjet heads 5 are mounted on the carriage 29. The inkjet heads 5 according to the present embodiment are each an inkjet head of an electromechanical transduction type in which ink is ejected from a head chip including an actuator plate formed of a piezoelectric element made of PZT (lead zirconate titanate) or the like.

In this inkjet head 5, in order to eject the ink, a voltage is applied between electrodes on drive walls of an ejection channel provided to the actuator plate to cause the drive wall to make a thickness-shear deformation. Thus, due to a change in volume of the ejection channel, the ink in the ejection channel is ejected through a nozzle hole. It should be noted that an ejection method of the liquid is not limited to an electromechanical transduction type described above, and it is possible to adopt a charge control method, a pressure vibration method, an electrothermal transduction method, an electrostatic suction method, and so on.

The charge control method is for providing a charge to a material with a charge electrode to eject the material from a nozzle while controlling a flight direction of the material with a deflection electrode. Further, the pressure vibration method is for applying super high pressure to the material to eject the material toward a nozzle tip, and when a control voltage is not applied, the material goes straight to be ejected from the nozzle, and when the control voltage is applied, an electrostatic repelling force is generated between the materials, and the material flies in all directions to be prevented from being ejected from the nozzle.

Further, the electrothermal transduction method is for rapidly vaporizing the material with a heater provided in a space containing the material to generate a bubble, to eject the material in the space with the pressure of the bubble. The electrostatic suction method is for applying minute pressure to a space retaining the material to form a meniscus in the nozzle, and then pulling the material out after applying an electrostatic attractive force in this state. Further, besides the above, it is possible to adopt technologies such as a method using a viscosity alteration of a fluid due to an electric field, or a method of flying the material with a discharge spark.

FIG. 3 is a plan view showing an arrangement of the inkjet heads 5 installed in the carriage 29 according to the embodiment.

As shown in FIG. 3, the plurality of inkjet heads 5 is mounted on an installation surface 29a of the carriage 29. The inkjet heads 5 each have a substantially rectangular

shape extending in the X direction in the plan view, wherein one side (the +X side) in the X direction thereof, there is disposed an entrance port **5a** to which the ink supply tube **21** described above is coupled, and on the other side (the-X side) in the X direction thereof, there is disposed an exit port **5b** to which the ink discharge tube **22** described above is coupled.

The inkjet heads **5** are each installed on the installation surface **29a** of the carriage **29** in an orientation in which a long side extends in the X direction, and a short side extends in the Y direction. The inkjet heads **5** are installed at a predetermined pitch in the X direction on the installation surface **29a**. On an upper surface of each of the inkjet heads **5**, there is disposed a coupling connector not shown to thereby electrically be coupled to the printer **1** via a cable not shown.

The carriage **29** is provided with insertion holes **29b** into which a lower end portion of the inkjet head **5** is inserted. The insertion holes **29b** are each an elongated hole having a rectangular shape extending in the X direction in the plan view, and each penetrate the installation surface **29a** of the carriage **29** in a thickness direction (the Z direction). The insertion holes **29b** are each formed to be one-size larger than the lower end portion of the inkjet head **5** to ensure a clearance for positioning of the inkjet head **5**. Each of the inkjet heads **5** are fixed to the carriage **29** while being adjusted in a position in the X direction, a position in the Y direction, and a rotational angle on the X-Y plane by a positioning structure **100** described below.

<Positioning Structure **100**>

FIG. 4 is a perspective view of the positioning structure **100** of the inkjet head **5** according to the embodiment. FIG. 5 is an exploded perspective view of the positioning structure **100** of the inkjet head **5** according to the embodiment. FIG. 6 is a plan view of the positioning structure **100** of the inkjet head **5** according to the embodiment.

As shown in these drawings, the inkjet head **5** is provided with a head main body **5A** (a jet section) for jetting the ink, and a base member **30** which supports the head main body **5A**, and is installed on the installation surface **29a** of the carriage **29**.

As shown in FIG. 5, the head main body **5A** has a rectangular box-like shape, and is provided with a nozzle array not shown for jetting the ink on a lower surface thereof. The base member **30** is coupled to the lower end portion of the head main body **5A**. The base member **30** is provided with a plate part **31** to be mounted on the installation surface **29a** of the carriage **29**, and a base part **32** which surrounds the lower end portion of the head main body **5A**.

The base part **32** has a rectangular box-like shape opening on an upper side. On a bottom surface of the base part **32**, there is formed an elongated hole not shown for exposing the nozzle array of the head main body **5A**. The plate part **31** has a plate shape extending from an upper opening edge of the base part **32** toward both sides in the X direction. The plate part **31** is fixed to the installation surface **29a** of the carriage **29** with screw members **101** each attached to the installation surface **29a** of the carriage **29** via a spring washer **101a**. The installation surface **29a** of the carriage **29** is provided with fixation holes **29d** to which the screw members **101** are screwed.

The plate part **31** of the base member **30** is provided with first penetration parts **33** in which positioning pins **40** (protruding parts) are arranged, and second penetration parts **34** in which the screw members **101** are arranged. The first penetration parts **33** each have an elongated hole shape extending in the X direction, and at the same time, are

formed to be one-size larger than the positioning pins **40**. Further, the second penetration parts **34** each have an elongated hole shape extending in the X direction, and at the same time, are each formed to be one-size larger than a shaft portion of the screw member **101**.

The base member **30** is arranged to be able to be adjusted in the fixation position in a direction (an X-Y plane direction) along the installation surface **29a** of the carriage **29** due to these gaps. Further, between the first penetration part **33** and the second penetration part **34** in the plate part **31**, there is a plurality of fixation holes **35** for fixing a positioning unit **50** described later. On an inner wall surface of the fixation hole **35**, there is formed an internal thread to which each of screw members **102** for fixing the positioning unit **50** is screwed.

The positioning structure **100** is provided with the positioning pins **40** provided to the carriage **29**, and the positioning units **50** which are provided to the inkjet head **5**, and which adjust a position of the base member **30** with respect to the positioning pins **40** in a direction along the installation surface **29a** of the carriage **29**. As the positioning pins **40**, the positioning structure **100** is provided with a first positioning pin **40A** and a second positioning pin **40B** arranged in the X direction across the head main body **5A**.

The first positioning pin **40A** is arranged at the +X side of the head main body **5A**. The second positioning pin **40B** is arranged at the-X side of the head main body **5A**. Further, as the positioning units **50**, the positioning structure **100** is provided with a first positioning unit **50A** for adjusting a position of the base member **30** with respect to the first positioning pin **40A**, and a second positioning unit **50B** for adjusting a position of the base member **30** with respect to the second positioning pin **40B**.

<Positioning Units **50**>

FIG. 7 is a perspective view of the first positioning unit **50A** according to the embodiment. FIG. 8 is a perspective view of the second positioning unit **50B** according to the embodiment. FIG. 9 is a cross-sectional view along an arrow IX-IX shown in FIG. 6.

As shown in FIG. 7, the first positioning unit **50A** is provided with a frame member **51**, and two positioning mechanisms **60** respectively in the X direction and the Y direction supported by the frame member **51**. In the following description, first, a basic structure of the positioning mechanisms **60** will be described based on the positioning mechanism **60** in the Y direction (hereinafter referred to as a second positioning mechanism **60B**).

The second positioning mechanism **60B** adjusts the position of the base member **30** in the Y direction along the installation surface **29a** with respect to the positioning pin **40** disposed on the installation surface **29a** of the carriage **29** described above. The second positioning mechanism **60B** is provided with a preloading mechanism **70** for preloading the positioning pin **40** in the Y direction along the installation surface **29a**, a contact member **80** making contact with the positioning pin **40** from an opposite side (the +Y side) to a side (the-Y side) at which the preloading mechanism **70** is arranged in the Y direction in which the preloading mechanism **70** applies the preload, and a displacement mechanism **90** for displacing the contact member **80** in the Y direction in which the preloading mechanism **70** applies the preload.

As shown in FIG. 9, the preloading mechanism **70** is provided with two plate springs **71**, **72**. The plate spring **71** is cranked, and a tip portion of the plate spring **71** has contact with the-Y side of the positioning pin **40**. The plate spring **72** bends to form an L shape, and overlaps a back side of the plate spring **71** to thereby adjust a biasing force of the

preloading mechanism 70. It should be noted that it is possible to make two or more plate springs 72 overlap the plate spring 71. Further, when the biasing force of the plate spring 71 is sufficient, it is not required to dispose the plate spring 72.

As shown in FIG. 7, the plate springs 71, 72 are fixed to a bottom part 52 of the frame member 51 with screw members 103. In the vicinity of the screw members 103, there is formed a plurality of third penetrating parts 52a penetrating the plate springs 71, 72 and the bottom part 52 of the frame member 51 in the Z direction. As shown in FIG. 9, in the third penetrating parts 52a, there are arranged the screw members 102 for fixing the second positioning unit 50B. The screw members 102 are screwed respectively to the fixation holes 35 provided to the plate part 31 of the base member 30. In other words, the second positioning unit 50B (the two positioning mechanisms 60) is detachably attached to the base member 30 with the screw members 102.

The displacement mechanism 90 displaces the contact member 80 having contact with the +Y side of the positioning pin 40 along a displacement axis O2 extending in an oblique direction crossing a direction (the Z direction) perpendicular to the installation surface 29a. The frame member 51 is provided with an attachment part 53 to which the displacement mechanism 90 is attached. The attachment part 53 bends at a right angle with the bottom part 52, and further bends at a substantially middle position in the height direction (the Z direction) at the same angle as that of the displacement axis O2 toward the bottom part 52 (toward the positioning pin 40). The attachment part 53 is provided with an opening part 54 for avoiding an interference with a lower end portion of the guide part 91 of the displacement mechanism 90. A back side of the guide part 91 is fixed to the attachment part 53 via screw members 104.

The guide part 91 is an orbital member which extends in an oblique direction along the displacement axis O2 to guide the contact member 80. The guide part 91 has a tilted surface having contact with the back side (+Y side) of the contact member 80. The contact member 80 has a clamping part 82 for clamping the guide part 91 in a direction (the X direction) perpendicular to the displacement axis O2. In other words, the contact member 80 is arranged to be able to be displaced in the oblique direction along the guide part 91 while sliding on three surfaces, namely the tilted surface and both side surfaces, of the guide part 91.

The displacement mechanism 90 is provided with the guide part 91 described above, a bolt 92, a compression spring 93, a first support part 94, and a second support part 95. The contact member 80 is threadably mounted on the bolt 92 so that screw feeding of the contact member 80 can be achieved. The bolt 92 extends along the displacement axis O2, and screw-feeds the contact member 80 with the rotation around the displacement axis O2. The first support part 94 is disposed in an upper end portion (one end portion) of the guide part 91 to support a head part of the bolt 92. The first support part 94 is provided with a first insertion hole 94a through which a shaft part of the bolt 92 is inserted. The first insertion hole 94a shaft-supports a portion (a neck portion) which is not provided with the thread in a shaft part of the bolt 92.

The compression spring 93 is, for example, a coil spring arranged around the bolt 92, and intervenes between the first support part 94 and the contact member 80. The compression spring 93 extends and contracts so as to fill a gap between the contact member 80 and the first support part 94 which varies due to the screw-feeding with the bolt 92. The second support part 95 is disposed in a lower end portion

(the other end portion) of the guide part 91. The second support part 95 is provided with a second insertion hole 95a through which the shaft part of the bolt 92 is inserted. The second insertion hole 95a shaft-supports a tip portion which is not provided with the thread in the shaft part of the bolt 92. The guide part 91 described above, the first support part 94, and the second support part 95 are integrally formed to have a substantially C shape as a whole.

The positioning pin 40 erects vertically to the installation surface 29a of the carriage 29. The positioning pin 40 is provided with a contact part 41, a chamfered part 42 (see FIG. 7), and a screw part 43 (see FIG. 9). The screw part 43 is disposed in a lower end portion of the positioning pin 40, and is screwed to a fixation hole 29c provided to the installation surface 29a of the carriage 29. As shown in FIG. 7, the chamfered part 42 is obtained by chamfering a part of a circumferential surface of the positioning pin 40 to form at least two surfaces parallel to each other to make it possible to screw the positioning pin 40. In other words, the positioning pin 40 is detachably attached to the carriage 29. It should be noted that it is possible for the chamfered part 42 to be what is obtained by performing the chamfering to form four surfaces or six surfaces.

As shown in FIG. 7, the positioning pin 40 has the contact part 41 shaped like a curved surface having contact with the contact member 80. Further, the contact member 80 has a contact part 81 shaped like a curved surface having contact with the positioning pin 40. A relationship between the curved surface shapes of the contact parts 41, 81 of the positioning pin 40 and the contact member 80 will herein-after be described with reference to FIG. 10.

FIG. 10 is a conceptual diagram for explaining the curved surface shapes of the contact parts 41, 81 according to the embodiment.

As shown in FIG. 10, the contact part 41 of the positioning pin 40 is formed to have the curved surface shape taking a first intersecting axis O1 crossing the installation surface 29a as a central axis. The first intersecting axis O1 in the present embodiment crosses perpendicularly to (at a right angle with) the installation surface 29a, but can obliquely cross the installation surface 29a.

The contact part 41 in the present embodiment includes a first cylindrical surface taking the first intersecting axis O1 as a central axis. It should be noted that the "first cylindrical surface" means a surface formed to have a constant radius with respect to the first intersecting axis O1. Further, "including the first cylindrical surface" only requires that at least a portion having contact with the contact member 80 is the first cylindrical surface, and can include that a plane (e.g., the chamfered part 42 shown in FIG. 7) or the like exists in other portions than the portion having contact with the contact member 80.

In contrast, the contact part 81 of the contact member 80 is formed to have a curved surface shape taking the second intersecting axis O3, which is nonparallel to the first intersecting axis O1, as a central axis. The second intersecting axis O3 crosses an imaginary plane 110 which includes the displacement axis O2 of the contact member 80 and a vertical axis O4 extending in a direction perpendicular to the installation surface 29a (or the first intersecting axis O1 in the present embodiment). The second intersecting axis O3 in the present embodiment extends in parallel to the installation surface 29a, and crosses perpendicularly to (at a right angle with) the imaginary plane 110, but can obliquely cross the imaginary plane 110.

The contact part 81 in the present embodiment includes a second cylindrical surface taking the second intersecting

11

axis O3 as a central axis. It should be noted that the “second cylindrical surface” means a surface formed to have a constant radius with respect to the second intersecting axis O3. Further, “including the second cylindrical surface” only requires that at least a portion having contact with the positioning pin 40 is the second cylindrical surface, and can include that planes (e.g., upper and lower parallel surfaces and left and right tilted surfaces of the contact part 81 shown in FIG. 7) or the like exist in other portions than the portion having contact with the positioning pin 40.

Incidentally, when it is supposed that the positioning pin 40 is a square protruding part, the contact part 81 of the contact member 80 is a tilted surface, and the tilted surface is made to have contact with a corner part of the protruding part, the corner part and the tilted surface make line contact with each other. However, since minute asperity caused by processing accuracy or the like exists on the corner part and the tilted surface, the corner part and the tilted surface have contact with each other at a number of points in a precise sense. In the state of the multipoint contact described above, since errors at respective contact points are apt to accumulate, there is a possibility that it becomes difficult to accurately position the inkjet head 5 to the carriage 29.

In contrast, according to the configuration described above, since the central axes (the first intersecting axis O1 and the second intersecting axis O3) of the respective curved surface shapes of the contact parts 41, 81 are in a skew positional relationship, the positioning pin 40 and the contact member 80 have contact with each other at a single point. Since the positioning pin 40 and the contact member 80 have contact with each other at the single point, it is possible to avoid the error due to the multipoint contact between the positioning pin 40 and the contact member 80, and thus, it is possible to accurately position the inkjet head 5 to the carriage 29. Further, since the displacement axis O2 extends in the oblique direction crossing the installation surface 29a, the displacement of the contact member 80 in a direction along the installation surface 29a per revolution of the bolt 92 decreases, and thus, it is possible to make a microscopic displacement of the contact member 80 with high accuracy.

The basic structure of the positioning mechanism 60 is hereinabove described.

The second positioning unit 50B shown in FIG. 8 is also provided with the same configuration as the positioning mechanism 60 (the second positioning mechanism 60B) in the Y direction of the first positioning unit 50A. It should be noted that a configuration of the positioning mechanism (the first positioning mechanism 60A) in the X direction is disposed in the first positioning unit 50A and the second positioning unit 50B in a separate manner. Although described later in detail, in the first positioning unit 50A shown in FIG. 7, there are disposed the contact member 80 and the displacement mechanism 90 of the first positioning mechanism 60A, and in the second positioning unit 50B shown in FIG. 8, there is disposed the preloading mechanism 70 of the first positioning mechanism 60A. The preloading mechanism 70 of the first positioning mechanism 60A is formed of a single plate spring 70A, and is fixed to a sidewall part 56 erected at the -X side of the frame member 51 via screw members 105.

<Arrangement of Positioning Structure 100>

As shown in FIG. 6, the positioning structure 100 is provided with the first positioning mechanism 60A for adjusting the position in the X direction (a first direction) along the installation surface 29a of the base member 30, and the pair of second positioning mechanisms 60B which

12

are arranged at a distance in the X direction to the base member 30, and which respectively adjust the positions in the Y direction (a second direction) perpendicular to the X direction along the installation surface 29a of the base member 30.

Further, the positioning structure 100 is provided with the first positioning pin 40A (a first protruding part) and the second positioning pin 40B (a second protruding part) arranged in the X direction across the head main body 5A.

One (the second positioning mechanism 60B at the first positioning unit 50A side) of the pair of second positioning mechanisms 60B adjusts the position in the Y direction of the base member 30 to the first positioning pin 40A. Further, the other (the second positioning mechanism 60B at the second positioning unit 50B side) of the pair of second positioning mechanisms 60B adjusts the position in the Y direction of the base member 30 to the second positioning pin 40B.

The preloading mechanism 70 (the plate spring 70A) of the first positioning mechanism 60A is disposed at the second positioning unit 50B side to apply the preload in the X direction to the second positioning pin 40B. Further, the contact member 80 and the displacement mechanism 90 of the first positioning mechanism 60A are disposed at the first positioning unit 50A side, and the contact member 80 makes contact with the first positioning pin 40A from an opposite side (the +X side) to the side (the -X side) at which the preloading mechanism 70 (the plate spring 70A) is arranged in the X direction, and at the same time, is displaced in the X direction.

Each of the positioning mechanisms 60 is supported by the base member 30, and at the same time, at least a part of the positioning mechanism 60 is arranged inside the outer shape of the base member 30 in the plan view of the installation surface 29a viewed from the vertical direction (the Z direction). It should be noted that the “inside of the outer shape of the base member 30” means an inside of an outline of the plate part 31 forming the outermost shape of the base member 30 in the plan view of the installation surface 29a viewed from the vertical direction (the Z direction).

Further, the positioning pins 40 are also arranged inside the outer shape of the base member 30. In other words, as shown in FIG. 5, the plate part 31 of the base member 30 is provided with the first penetration parts 33 in which the positioning pins 40 are arranged, and which are formed inside the outer shape of the base member 30. In other words, since the positioning pins 40 are arranged so as to penetrate the base member 30, and the base member 30 supports the positioning mechanisms 60, the positioning structure 100 is arranged so that a large portion of the positioning structure 100 overlaps the footprint of the inkjet head 5.

The plate part 31 of the base member 30 is provided with pressing parts 36, 37 (protrusions) each protruding toward a side at which the preloading mechanism 70 receives a reactive force from the positioning pin 40 in a direction in which the preloading mechanism 70 applies the preload. The pressing parts 36 are each disposed so as to protrude toward a side (the -Y side) at which the preloading mechanism 70 receives the reactive force from the positioning pin 40 in the Y direction in which the preloading mechanism 70 of the second positioning mechanism 60B applies the preload. Further, the pressing part 37 is disposed so as to protrude toward a side (the -X side) at which the preloading mechanism 70 receives the reactive force from the positioning pin

40 in the X direction in which the preloading mechanism 70 of the first positioning mechanism 60A applies the preload.

In contrast, the carriage 29 is provided with receiving parts 36A, 37A which the pressing parts 36, 37 are pressed against, respectively. The receiving parts 36A, 37A are for substantially positioning the inkjet head 5 to the carriage 29 in a state in which the pressing parts 36, 37 are pressed. It should be noted that it is desirable to complete the positioning of the inkjet head 5 in the state in which the pressing parts 36, 37 are pressed against the receiving parts 36A, 37A, respectively, but it is necessary to process the pressing parts 36, 37 and the receiving parts 36A, 37A with high accuracy, which is high in cost, and therefore, a fine adjustment of the inkjet head 5 becomes necessary in most cases. Therefore, it is necessary to adjust the position of the inkjet head 5 in a direction along the installation surface 29a using the positioning structure 100 described above.

<Method of Positioning Inkjet Head 5>

For example, when translating the inkjet head 5 shown in FIG. 6 toward the +X side with respect to the carriage 29, the bolt 92 of the displacement mechanism 90 of the first positioning mechanism 60A is rotated to displace the contact member 80 toward the -X side with respect to the displacement mechanism 90. Then, the base member 30 to which the displacement mechanism 90 is fixed receives the reactive force from the first positioning pin 40A, and is translated toward the +X side along the installation surface 29a of the carriage 29 against the biasing force by the preloading mechanism 70. According to the above, it is possible to translate the inkjet head 5 toward the +X side with respect to the carriage 29.

When translating the inkjet head 5 toward the -X side with respect to the carriage 29, the bolt 92 of the displacement mechanism 90 of the first positioning mechanism 60A is rotated to displace the contact member 80 toward the +X side with respect to the displacement mechanism 90. Then, the base member 30 to which the displacement mechanism 90 is fixed receives the reactive force from the first positioning pin 40A, and is translated toward the -X side along the installation surface 29a of the carriage 29 against the biasing force by the preloading mechanism 70. According to the above, it is possible to translate the inkjet head 5 toward the -X side with respect to the carriage 29.

When translating the inkjet head 5 toward the +Y side with respect to the carriage 29, the bolt 92 of the displacement mechanism 90 of each of the pair of second positioning mechanisms 60B is rotated to displace the contact member 80 toward the -Y side with respect to the displacement mechanism 90. Then, the base member 30 to which the displacement mechanism 90 is fixed receives the reactive force from each of the positioning pins 40, and is translated toward the +Y side along the installation surface 29a of the carriage 29 against the biasing force by the preloading mechanism 70. According to the above, it is possible to translate the inkjet head 5 toward the +Y side with respect to the carriage 29.

When translating the inkjet head 5 toward the -Y side with respect to the carriage 29, the bolt 92 of the displacement mechanism 90 of each of the pair of second positioning mechanisms 60B is rotated to displace the contact member 80 toward the +Y side with respect to the displacement mechanism 90. Then, the base member 30 to which the displacement mechanism 90 is fixed receives the reactive force from each of the positioning pins 40, and is translated toward the -Y side along the installation surface 29a of the

carriage 29. According to the above, it is possible to translate the inkjet head 5 toward the -Y side with respect to the carriage 29.

When rotating the inkjet head 5 on the X-Y plane with respect to the carriage 29, the bolt 92 of the displacement mechanism 90 of each of the pair of second positioning mechanisms 60B is rotated to make the displacements (adjustment amounts) in the Y direction of the respective contact members 80 different from each other. Then, the base member 30 to which the displacement mechanism 90 is fixed receives the reactive forces different from each other from the respective positioning pins 40, and rotates along the installation surface 29a of the carriage 29. According to the above, it is possible to rotate the inkjet head 5 on the X-Y plane with respect to the carriage 29.

As a procedure of positioning the inkjet head 5 to the carriage 29, first, the spring washers 101a each intervening between the screw member 101 and the base member 30 are clamped with the screw members 101 to some extent to create a state in which the inkjet head 5 is temporarily fixed to the carriage 29 with the biasing force by the spring washers 101a (a temporary fixation step). Then, a rotational angle of the inkjet head 5 is adjusted using the pair of second positioning mechanisms 60B, and then, the inkjet head 5 is translated in the X direction and the Y direction using the first positioning mechanism 60A and the pair of second positioning mechanisms 60B. After the positioning of the inkjet head 5 to the carriage 29 is completed, the two screw members 101 at both sides in the X direction of the inkjet head 5 are completely tightened to fix the base member 30 to the carriage 29. According to the above, the installation of the inkjet head 5 to the carriage 29 is completed.

It should be noted that the positioning in the Y direction of the inkjet head 5 can be adjusted by an ink ejection timing. Therefore, when the positioning in the Y direction of the inkjet head 5 is unnecessary, the positioning is completed by two steps, namely the rotation of the inkjet head 5 and the translation in the X direction of the inkjet head 5. When the positioning in the Y direction of the inkjet head 5 is necessary, the positioning is completed by three steps, namely the rotation of the inkjet head 5, the translation in the Y direction of the inkjet head 5, and the translation in the X direction of the inkjet head 5.

FIG. 11 is an explanatory diagram showing a step subsequent to the positioning of the inkjet head 5 according to the embodiment.

After the positioning of the inkjet head 5 to the carriage 29 is completed, it is possible to detach the positioning structure 100 as shown in FIG. 11. Specifically, the screw members 102 shown in FIG. 9 are detached to detach the positioning unit 50 from the base member 30. Then, the positioning pin 40 provided with the chamfered part 42 is screwed with a tool such as a driver bit to detach the positioning pin 40 from the carriage 29. Lastly, another screw member 101 is screwed into the fixation hole 29c to which the positioning pin 40 has once been fixed, to thereby fix the base member 30 to the carriage 29. The positioning structure 100 detached here can be used again for positioning another inkjet head 5.

The positioning structure 100 described above can also adopt a modified example described hereinafter. It should be noted that in the following description, the constituents 65 same as or substantially the same as the constituents described above are denoted by the same reference symbols, and the explanation thereof will be simplified or omitted.

15

FIG. 12 is a cross-sectional view showing the modified example of the positioning structure 100 according to the embodiment.

The positioning structure 100 shown in FIG. 12 is different from the positioning structure 100 described above in the point that the positioning pin 40 is disposed at the base member 30 side of the inkjet head 5, and the positioning mechanism 60 (the positioning unit 50) is disposed at the carriage 29 side.

The base member 30 shown in FIG. 12 is fixed to an installation surface 29e facing below the carriage 29 with the screw members 101 each attached via the spring washer 101a. The carriage 29 is provided with a fourth penetration part 29g in which the positioning pin 40 provided to the base member 30 is arranged so as to penetrate in the Z direction, and a groove part 29h which is communicated with the -Z side of the fourth penetration part 29g and avoids interference with a flange part 44 of the positioning pin 40 and screw members 106.

The positioning pin 40 has the flange part 44 in a lower end portion, and the flange part 44 is fixed to an upper surface of the base member 30 via the screw members 106. The base member 30 is provided with fixation holes 38 to which the screw members 106 are respectively screwed. On the installation surface 29a (an upper surface) of the carriage 29, there are formed fixation holes 29f for fixing the positioning unit 50. The positioning unit 50 is detachably attached to the installation surface 29a of the carriage 29 with the screw members 102 respectively screwed into the fixation holes 29f.

Also in the configuration described above, by displacing the contact member 80 along the displacement axis O2, it is possible to adjust the position of the base member 30 in a direction along the installation surface 29a.

According to the present embodiment described above, the following functions and advantages can be obtained.

As shown in FIG. 6, the inkjet head 5 according to the present embodiment is provided with the head main body 5A for jetting the ink, the base member 30 which supports the head main body 5A, and is installed on the installation surface 29a of the carriage 29, and the positioning mechanisms 60 each of which adjusts the position of the base member 30 in the direction along the installation surface 29a with respect to the positioning pin 40 disposed on the installation surface 29a, wherein the positioning mechanisms 60 are supported by the base member 30, and at least a part of the positioning mechanisms 60 is arranged inside the outer shape of the base member 30 in the plan view of the installation surface 29a viewed from the vertical direction.

According to this configuration, since the positioning mechanisms 60 for positioning the inkjet head 5 with respect to the positioning pin 40 disposed on the installation surface 29a of the carriage 29 are supported by the base member 30 together with the head main body 5A, and at the same time, at least a part of the positioning mechanisms 60 is arranged inside the outer shape of the base member 30 in the plan view of the installation surface 29a viewed from the vertical direction, it is possible to arrange the positioning mechanisms 60 so as to overlap the footprint of the inkjet head 5, and thus, it is possible to reduce the area necessary to install the inkjet head 5. Thus, it is possible to suppress the length in the printing width direction (the X direction) of the inkjet head 5 to shorten the length in the printing width direction (the X direction) of the carriage 29 necessary when installing the plurality of inkjet heads 5.

16

Further, in the inkjet head 5 according to the present embodiment, as shown in FIG. 5, the base member 30 has the first penetration parts 33 inside the outer shape of the base member 30, wherein the positioning pins 40 are respectively arranged in the first penetration parts 33. According to this configuration, by providing the first penetration parts 33 to the base member 30, it is possible to arrange the positioning pins 40 inside the footprint of the inkjet head 5, and thus, it is possible to further reduce the area necessary to install the inkjet head 5.

Further, in the inkjet head 5 according to the present embodiment, as shown in FIG. 9, the positioning mechanism 60 is provided with the preloading mechanism 70 for preloading the positioning pin 40 in the direction along the installation surface 29a, the contact member 80 making contact with the positioning pin 40 from the opposite side to the side at which the preloading mechanism 70 is arranged in the direction in which the preloading mechanism 70 applies the preload, and the displacement mechanism 90 for displacing the contact member 80 in the direction in which the preloading mechanism 70 applies the preload. According to this configuration, by preloading the positioning pin 40 with the preloading mechanism 70 to displace the contact member 80 having contact with the positioning pin 40 in the preloading direction, it is possible to move the base member 30 following the displacement of the contact member 80. Since it becomes unnecessary to dispose the contact members 80 and the displacement mechanisms 90 at both sides across the positioning pin 40 due to the preloading mechanism 70, it is possible to achieve simplification, reduction in weight, and reduction in space of the structure of the positioning mechanism 60.

Further, in the inkjet head 5 according to the present embodiment, the positioning mechanism 60 (the positioning unit 50) is detachably attached to the base member 30. According to this configuration, since it is possible to detach the positioning mechanism 60 (the positioning unit 50) from the base member 30 after the positioning and the installation of the inkjet head 5 are completed, and then use the positioning mechanism 60 thus detached for positioning another inkjet head 5, this configuration can make a contribution to the reduction in cost.

Further, in the inkjet head 5 according to the present embodiment, as shown in FIG. 6, the positioning mechanisms 60 include the first positioning mechanism 60A for adjusting the position in the X direction (the first direction) along the installation surface 29a of the base member 30, and the pair of second positioning mechanisms 60B which are arranged at a distance in the X direction to the base member 30, and which respectively adjust the positions in the Y direction (the second direction) perpendicular to the X direction along the installation surface 29a of the base member 30. According to this configuration, it is possible to adjust the positions in the X direction and the Y direction along the installation surface 29a of the base member 30 using the first positioning mechanism 60A and the second positioning mechanisms 60B. Further, by making the adjustment amount of the position in the Y direction different between the pair of second positioning mechanisms 60B, it is possible to adjust the rotational angle of the base member 30.

Further, in the inkjet head 5 according to the present embodiment, the positioning pins 40 include the first positioning pin 40A and the second positioning pin 40B arranged across the head main body 5A in the X direction, wherein one (the second positioning mechanism 60B at the first positioning unit 50A side) of the pair of second positioning

mechanisms 60B adjusts the position of the base member 30 in the Y direction with respect to one (the first positioning pin 40A) of the first positioning pin 40A and the second positioning pin 40B, and the other (the second positioning mechanism 60B at the second positioning unit 50B side) of the pair of second positioning mechanisms 60B adjusts the position of the base member 30 in the Y direction with respect to the other (the second positioning pin 40B) of the first positioning pin 40A and the second positioning pin 40B. According to this configuration, since it is possible to position the inkjet head 5 with the two positioning pins 40 without disposing three positioning pins 40 so as to correspond respectively to the three positioning mechanisms 60, namely the first positioning mechanism 60A and the pair of second positioning mechanisms 60B, it is possible to decrease the number of the positioning pins 40 to be arranged in the footprint of the inkjet head 5 to thereby further reduce the area necessary to install the inkjet head 5.

Further, in the inkjet head 5 according to the present embodiment, the first positioning mechanism 60A is provided with the preloading mechanism 70 for applying the preload in the X direction to one (the second positioning pin 40B) of the first positioning pin 40A and the second positioning pin 40B, the contact member 80 making contact with the other (the first positioning pin 40A) of the first positioning pin 40A and the second positioning pin 40B from the opposite side to the side at which the preloading mechanism 70 is arranged in the X direction, and the displacement mechanism 90 for displacing the contact member 80 in the X direction. According to this configuration, by arranging the preloading mechanism 70 at the opposite side across the head main body 5A from the contact member 80 and the displacement mechanism 90, it is possible to suppress the length in the printing width direction (the X direction) of the base member 30 compared to when arranging all of the preloading mechanism 70, the contact member 80, and the displacement mechanism 90 at one side of the head main body 5A. Thus, it is possible to ensure the degree of freedom of the installation space of the inkjet head 5.

Further, in the inkjet head 5 according to the present embodiment, the outer shape of the base member 30 is provided with the pressing parts 36, 37 each protruding toward the side at which the preloading mechanism 70 receives the reactive force from the positioning pin 40 in the direction in which the preloading mechanism 70 applies the preload. According to this configuration, when the accuracy of the pressing parts 36, 37 is high, it is possible to easily position the inkjet head 5 by pressing the pressing parts 36, 37 against the carriage 29 with the reactive force received by the preloading mechanism 70 from the positioning pin 40. Further, when the accuracy of the pressing parts 36, 37 is insufficient, by displacing the contact member 80 toward the opposite side to the pressing direction of the pressing parts 36, 37 to adjust the position of the inkjet head 5, it is possible to position the inkjet head 5.

The printer 1 according to the present embodiment is provided with the inkjet heads 5 described above, and the carriage 29 as the installation target of the inkjet heads 5. According to this printer 1, there can be obtained the printer 1 which is capable of reducing the area necessary to install the inkjet heads 5, which is compact in size, and which is capable of performing accurate printing.

Further, in the printer 1 according to the present embodiment, the positioning pins 40 are detachably attached to the carriage 29. According to this configuration, since it is possible to detach the positioning pins 40 from the carriage 29 after the positioning and the installation of the inkjet head

5 are completed, and then use the positioning pins 40 thus detached for positioning another inkjet head 5, it becomes possible to use the positioning pins 40 for many occasions, which can make a contribution to the reduction in cost. 5 Further, it is possible to fix the base member 30 to the carriage 29 using the places where the positioning pins 40 are detached.

As shown in FIG. 12, the printer 1 according to the modified example of the present embodiment is provided 10 with the inkjet heads 5 and the carriage 29 on which the inkjet heads 5 are mounted, and the inkjet heads 5 are each provided with the head main body 5A for jetting the ink, the base member 30 which supports the head main body 5A, and is installed on the installation surface 29a of the carriage 29, 15 and the positioning pins 40 protruding from the base member 30 toward the carriage 29, the carriage 29 is provided with the positioning mechanisms 60 each of which adjusts the position of the base member 30 in the direction along the installation surface 29e with respect to the positioning pins 40, 20 and at least a part of the positioning mechanisms 60 is arranged inside the outer shape of the base member 30 in the plan view of the installation surface 29a viewed from the vertical direction.

According to the printer 1, since the inkjet head 5 is 25 provided with the positioning pins 40, the carriage 29 is provided with the positioning mechanisms 60, and at least a part of the positioning mechanisms 60 is arranged inside the outer shape of the base member 30 of the inkjet head 5 in the plan view of the installation surface 29e viewed from the 30 vertical direction, it is possible to arrange the positioning mechanisms 60 so as to overlap the footprint of the inkjet head 5, and thus, it is possible to decrease the area necessary to install the inkjet head 5. Thus, it is possible to suppress the 35 length in the printing width direction of the inkjet head 5 to shorten the length in the printing width direction of the carriage 29 necessary when installing the plurality of inkjet heads 5.

Further, according to the present embodiment described 40 above, the following functions and advantages can be obtained.

The positioning structure 100 according to the present embodiment is the positioning structure 100 for positioning the inkjet head 5 to the carriage 29 of the printer 1, and is provided with the positioning pins 40 provided to one of the carriage 29 and the inkjet head 5, and the positioning mechanisms 60 which are provided to the other of the carriage 29 and the inkjet head 5, and which adjust the positions in the direction along the installation surface 29a of the carriage 29 with respect to the positioning pins 40, 45 wherein the positioning mechanisms 60 each include the contact member 80 having contact with the positioning pin 40, and the displacement mechanism 90 for displacing the contact member 80 along the displacement axis O2 extending in the oblique direction crossing the direction perpendicular to the installation surface 29a, one of the contact parts 41, 81 of the positioning pin 40 and the contact member 80 is formed to have the curved surface shape taking the first intersecting axis O1 crossing the installation surface 29a as the central axis, and the other of the contact parts 41, 81 is formed to have the curved surface shape taking the second intersecting axis O3 as the central axis, the second intersecting axis O3 crossing the imaginary plane 110 (see FIG. 10) including the displacement axis O2 and the vertical axis O4 (the first intersecting axis O1) extending 50 in the direction perpendicular to the installation surface 29a, and the second intersecting axis O3 being nonparallel to the first intersecting axis O1.

According to this configuration, when the contact member **80** is displaced in the oblique direction crossing the direction perpendicular to the installation surface **29a** due to the displacement mechanism **90**, the positioning pin **40** having contact with the contact member **80** is pressed in the direction along the installation surface **29a**, and thus, the inkjet head **5** is displaced with respect to the carriage **29**. Here, since one of the contact parts **41, 81** is formed to have the curved surface shape taking the first intersecting axis **O1** crossing the installation surface **29a** as the central axis, and at the same time, the other of the contact parts **41, 81** is formed to have the curved surface shape taking the second intersecting axis **O3** as the central axis, the second intersecting axis **O3** crossing the imaginary plane **110** including the displacement axis **O2** and the vertical axis extending in the direction perpendicular to the installation surface **29a**, and the second intersecting axis **O3** being nonparallel to the first intersecting axis **O1**, and the central axes of the respective curved surface shapes of the contact parts **41, 81** become in the skew positional relationship, the positioning pin **40** and the contact member **80** have contact with each other at a single point. Since the positioning pin **40** and the contact member **80** have contact with each other at the single point, it is possible to avoid the error due to the multipoint contact between the positioning pin **40** and the contact member **80**, and thus, it is possible to accurately position the inkjet head **5** to the carriage **29**.

Further, in the positioning structure **100** according to the present embodiment, one (the contact part **41**) of the contact parts **41, 81** includes the first cylindrical surface taking the first intersecting axis **O1** as the central axis, and the other (the contact part **81**) of the contact parts **41, 81** includes the second cylindrical surface taking the second intersecting axis **O3** as the central axis. According to this configuration, since the contact part **41** of the positioning pin **40** as the one of the contact parts has the first cylindrical surface taking the first intersecting axis **O1** as the central axis, the contact part **81** of the contact member **80** has the second cylindrical surface taking the second intersecting axis **O3** as the central axis, and the central axes (the first intersecting axis **O1** and the second intersecting axis **O3**) of the both parties cross each other, it is possible to make the positioning pin **40** and the contact member **80** always have stable contact with each other at the single point.

Further, in the positioning structure **100** according to the present embodiment, the contact part **41** of the positioning pin **40** includes the first cylindrical surface extending in the direction perpendicular to the installation surface **29a**, and the contact part **81** of the contact member **80** includes the second cylindrical surface extending in parallel to the installation surface **29a**. According to this configuration, since the contact part **41** of the positioning pin **40** includes the first cylindrical surface extending in the direction perpendicular to the installation surface **29a**, and the contact part **81** of the contact member **80** includes the second cylindrical surface extending in parallel to the installation surface **29a**, the positioning pin **40** and the contact member **80** always make stable contact with each other at the single point, and at the same time, it is possible to prevent the contact member **80** having contact with the positioning pin **40** at the single point from being shifted in the direction (the X-Y plane direction) along the installation surface **29a** with respect to the positioning pin **40**.

Further, in the positioning structure **100** according to the present embodiment, the displacement mechanism **90** has the guide part **91** which extends in the oblique direction along the displacement axis **O2** to guide the contact member

80. According to this configuration, it is possible to accurately displace the contact member **80** in the oblique direction along the guide part **91**.

Further, in the positioning structure **100** according to the present embodiment, the contact member **80** has the clamping part **82** for clamping the guide part **91** in the direction perpendicular to the displacement axis **O2**. According to this configuration, by clamping the guide part **91** with the clamping part **82** provided to the contact member **80**, it is possible to prevent the contact member **80** from rotating around the displacement axis **O2**.

Further, in the positioning structure **100** according to the present embodiment, the displacement mechanism **90** includes the bolt **92** which extends along the displacement axis **O2**, and which screw-feeds the contact member **80**, the first support part **94** which is disposed in one end portion of the guide part **91**, which supports the head part of the bolt **92**, and which is provided with the first insertion hole **94a** through which the shaft part of the bolt **92** is inserted, and the compression spring **93** arranged between the first support part **94** and the contact member **80**. According to this configuration, when rotating the bolt **92** forming the displacement axis **O2**, the contact member **80** which has the clamping part **82**, and which is restricted in the rotation with respect to the guide part **91** is screw-fed. On this occasion, a gap between the first support part **94** and the contact member **80** increases, but the compression spring **93** expands so as to fill the gap, and therefore, it is possible to prevent the head part of the bolt **92** from lifting from the first support part **94**.

Further, in the positioning structure **100** according to the present embodiment, the displacement mechanism **90** has the second support part **95** which is disposed in the other end portion of the guide part **91**, and which is provided with the second insertion hole **95a** through which the shaft part of the bolt **92** is inserted. According to this configuration, since it is possible to shaft-support the both ends of the bolt **92** with the first support part and the second support part **95** by inserting the shaft part of the bolt **92** into the second insertion hole **95a** of the second support part **95**, it is possible to suppress the shaft wobbling of the bolt **92** to thereby displace the contact member **80** with high accuracy.

Further, in the positioning structure **100** according to the present embodiment, the positioning mechanism **60** is provided with the preloading mechanism **70** for applying the preload in the direction along the installation surface **29a** to the positioning pin **40** from the opposite side to the side at which the contact member **80** is arranged. According to this configuration, by preloading the positioning pin **40** with the preloading mechanism **70** to displace the contact member **80** having contact with the positioning pin **40** in the preloading direction, it is possible to move the base member **30** following the displacement of the contact member **80**. Since it becomes unnecessary to dispose the contact members **80** and the displacement mechanisms **90** at both sides across the positioning pin **40** due to this preloading mechanism **70**, it is possible to achieve simplification, reduction in weight, and reduction in space of the structure of the positioning mechanism **60**.

The inkjet head **5** according to the present embodiment is provided with either one of the positioning mechanism **60** and the positioning pin **40** of the positioning structure **100** described above. According to this inkjet head **5**, it is possible to obtain the inkjet head **5** capable of performing accurate printing.

21

The printer 1 according to the present embodiment is provided with the positioning structure 100 described above. According to this printer 1, it is possible to perform accurate printing.

The printer 1 according to the present embodiment is provided with the inkjet heads 5, the carriage 29 on which the inkjet heads 5 are installed, and the positioning structure 100 described above for positioning the inkjet head 5 to the carriage 29. According to this printer 1, it is possible to accurately position the inkjet head 5 to the carriage 29 of the printer 1 to perform accurate printing.

Although the preferred embodiment of the present disclosure is hereinabove described, it should be understood that this is an illustrative description of the present disclosure, and should not be considered as a limitation. Modification such as addition, omission, and displacement can be implemented within the scope or the spirit of the present disclosure. Therefore, the present disclosure should not be assumed to be limited by the above description, but is limited by the appended claims.

For example, in the embodiment described above, there is illustrated the detachable positioning pin 40 as the protruding part of the positioning structure 100, but this configuration is not a limitation. The protruding part of the positioning structure 100 can also be integrally provided to the inkjet head 5 or the carriage 29, and can be not detachable.

Further, for example, in the embodiment described above, there is illustrated the positioning unit 50 in which a part of the first positioning mechanism 60A and the second positioning mechanism 60B are unitized, but this configuration is not a limitation. It is possible for the first positioning mechanism 60A and the second positioning mechanism 60B to individually be attached to the inkjet head 5 or the carriage 29.

Further, for example, in the embodiment described above, there is illustrated an aspect in which the contact part 41 of the positioning pin 40 and the contact part 81 of the contact member 80 each have the cylindrical surface, but this configuration is not a limitation. The contact parts 41, 81 can have any curved surface shapes providing the contact parts 41, 81 have contact with each other at a single point. In other words, the "curved surface shape" is not only the curved surface which is formed with a constant radius from the central axis, and the cross-sectional shape of which is a true circle, but can be, for example, a curved surface the cross-sectional shape of which is an elliptical shape, or a curved surface which can be defined by a quadratic function.

Further, for example, in the embodiment described above, the description is presented citing the inkjet printer as an example of the liquid jet recording device, but the liquid jet recording device is not limited to the printer. For example, a facsimile machine, an on-demand printing machine, and so on can also be adopted.

In the embodiment described above, the description is presented citing the configuration (a so-called shuttle machine) in which the inkjet head moves with respect to the recording target medium when performing printing as an example, but this configuration is not a limitation. The configuration related to the present disclosure can be adopted as the configuration (a so-called stationary head machine) in which the recording target medium is moved with respect to the inkjet head in the state in which the inkjet head is fixed.

In the embodiment described above, there is described a case when the recording target medium P is paper, but this configuration is not a limitation. The recording target

22

medium P is not limited to paper, but can also be a metal material or a resin material, and can also be food or the like.

In the embodiment described above, there is described the configuration in which the liquid jet head is installed in the liquid jet recording device, but this configuration is not a limitation. Specifically, the liquid to be jetted from the liquid jet head is not limited to what is landed on the recording target medium, but can also be, for example, a medical solution to be blended during a dispensing process, a food additive such as seasoning or a spice to be added to food, or fragrance to be sprayed in the air.

In the embodiment described above, there is described the configuration in which the Z direction coincides with the gravitational direction, but this configuration is not a limitation, and it is also possible to set the Z direction along the horizontal direction.

In the embodiment described above, there is described the configuration in which the first direction coincides with the X direction, and the second direction coincides with the Y direction, but this configuration is not a limitation. The first direction and the second direction can be defined differently from the X direction and the Y direction.

What is claimed is:

1. A liquid jet head comprising:
a jet section configured to jet liquid;
a base member which is configured to support the jet section, and which is installed on an installation surface of an installation target; and
a positioning mechanism configured to adjust a position of the base member in a direction along the installation surface with respect to a protruding part disposed on the installation surface,
wherein the positioning mechanism is supported by the base member,
wherein at least a part of the positioning mechanism is arranged inside an outer shape of the base member in a plan view of the installation surface viewed from a vertical direction thereof,
wherein the positioning mechanism includes:
a first positioning mechanism configured to adjust a position of the base member in a first direction along the installation surface of the base member; and
a pair of second positioning mechanisms which are arranged at a distance in the first direction to the base member, and which respectively adjust positions of the base member in a second direction perpendicular to the first direction along the installation surface of the base member,
wherein the protruding part includes a first protruding part and a second protruding part arranged across the jet section in the first direction,
one of the pair of second positioning mechanisms adjusts a position of the base member in the second direction with respect to one of the first protruding part and the second protruding part, and
another of the pair of second positioning mechanisms adjusts a position of the base member in the second direction with respect to another of the first protruding part and the second protruding part, and
wherein the first positioning mechanism includes:
a preloading mechanism configured to preload one of the first protruding part and the second protruding part in the first direction,
a contact member making contact with another of the first protruding part and the second protruding part from an opposite side to a side at which the preloading member is arranged in the first direction; and

23

- a displacement mechanism configured to displace the contact member in the first direction.
2. The liquid jet head according to claim 1, wherein the base member has a penetration part inside the outer shape of the base member, the protruding part being arranged in the penetration part. 5
3. The liquid jet head according to claim 1, wherein the positioning mechanism includes:
- a preloading mechanism configured to apply a preload to the protruding part in a direction along the installation surface,
  - a contact member having contact with the protruding part from an opposite side to a side at which the preloading mechanism is arranged in a direction in which the preloading mechanism applies the preload; and 10
  - a displacement mechanism configured to displace the contact member in the direction in which the preloading mechanism applies the preload.
4. The liquid jet head according to claim 3, wherein a pressing part protruding toward a side at which the preloading mechanism receives a reactive force from the protruding part in the direction in which the preloading mechanism applies the preload is provided to the outer shape of the base member. 15
5. The liquid jet head according to claim 1, wherein the positioning mechanism is detachably attached to the base member. 20
6. A liquid jet recording device comprising:
- the liquid jet head according to claim 1; and
  - a carriage as the installation target on which the liquid jet head is installed.
7. The liquid jet recording device according to claim 6, wherein the protruding part is detachably attached to the carriage. 25
8. A liquid jet recording device comprising:
- a liquid jet head; and
  - a carriage on which the liquid jet head is installed, wherein
  - the liquid jet head includes
  - a jet section configured to jet liquid,
  - a base member which is configured to support the jet section, and which is installed on an installation surface of the carriage, and
- 30
- 35
- 40

24

- a protruding part protruding from the base member toward the carriage, the carriage is provided with a positioning mechanism configured to adjust a position of the base member in a direction along the installation surface with respect to the protruding part, and at least a part of the positioning mechanism is arranged inside an outer shape of the base member in a plan view of the installation surface viewed from a vertical direction thereof, wherein the positioning mechanism includes:
- a first positioning mechanism configured to adjust a position of the base member in a first direction along the installation surface of the base member; and
  - a pair of second positioning mechanisms which are arranged at a distance in the first direction to the base member, and which respectively adjust positions of the base member in a second direction perpendicular to the first direction along the installation surface of the base member,
- wherein the protruding part includes a first protruding part and a second protruding part arranged across the jet section in the first direction, one of the pair of second positioning mechanisms adjusts a position of the base member in the second direction with respect to one of the first protruding part and the second protruding part, and another of the pair of second positioning mechanisms adjusts a position of the base member in the second direction with respect to another of the first protruding part and the second protruding part, and wherein the first positioning mechanism includes:
- a preloading mechanism configured to preload one of the first protruding part and the second protruding part in the first direction,
  - a contact member making contact with another of the first protruding part and the second protruding part from an opposite side to a side at which the preloading member is arranged in the first direction; and
  - a displacement mechanism configured to displace the contact member in the first direction.
